(57) CLAIM

The ornamental design for an automobile front grille, as shown and described.

DESCRIPTION

FIG. 1 is a perspective view of an automobile front grille;

FIG. 2 is a front view thereof;

FIG. 3 is a left side view thereof; and,

FIG. 4 is a top view thereof.

The broken lines in the drawings depict portions of the article that form no part of the claimed design.

1 Claim, 4 Drawing Sheets
